PROPELLER

Le Roy Martens, 1633 Palmyra Ave., Orange, Calif.

Filed July 20, 1964, Ser. No. 80,926

Term of patent 14 years

(Cl. D71—1)

FIGURE 1 is a front end elevation of a propeller showing my new design;

FIGURE 2 is a cross-sectional view thereof taken on line 2—2 of FIGURE 1; and

FIGURE 3 is a front perspective view of the same.

I claim:

The ornamental design for a propeller, substantially as shown.
